CLAIM

The ornamental design for an electrical receptacle with guide light and cover, as shown and described.

DESCRIPTION

FIG. 1 is a front perspective view of an electrical receptacle with guide light and cover showing the new design;

FIG. 2 is first exploded front perspective view thereof;

FIG. 3 is a front elevation view thereof;

FIG. 4 is a right side elevation view thereof;

FIG. 5 is a left side elevation view thereof;

FIG. 6 is a rear elevation view thereof;

FIG. 7 is a bottom plan view thereof;

FIG. 8 is a top plan view thereof;

FIG. 9 is a second exploded front perspective view thereof; and,

FIG. 10 is a third exploded front perspective view thereof. The broken lines in the drawings are for the purpose of illustrating portions of the article that form no part of the claimed design.

1 Claim, 10 Drawing Sheets
